AUTOMOBILE CONSOLE

David E. Rogers, 147 Highland Ave.,
Hamden, Conn. 06247

Continuation-in-part of abandoned design application Ser. No. 315,512, Dec. 15, 1972. This application June 10, 1974, Ser. No. 477,853

Term of patent 14 years

Int. Cl. D12—16

U.S. Cl. D12—155

Fig. 5.

Fig. 6.

Fig. 7.

Fig. 10.

Fig. 11.

Fig. 12.

Fig. 13.

Fig. 14.

Fig. 15.

Fig. 16.

FIG. 1 is a side elevational view of an automobile console showing my new design;

FIG. 2 is a side elevational view of the side opposite to that shown in FIG. 1;

FIG. 3 is a front elevational view thereof;

FIG. 4 is a rear elevational view thereof;

FIG. 5 is a top plan view thereof;

FIG. 6 is a bottom plan view thereof;

FIG. 7 is a cross-sectional view thereof taken along the line 7-7 of FIG. 3;

FIG. 8 is a cross-sectional view taken along the line 8-8 of FIG. 7;

FIG. 9 is a top plan view thereof, showing the hinged tops in their open horizontal position.

FIG. 10 is a side elevational view of an automobile console showing a second embodiment of my new design;

FIG. 11 is a side elevational view of the side opposite to that shown in FIG. 10;

FIG. 12 is a front elevational view of the embodiment shown in FIG. 10;

FIG. 13 is a rear elevational view of the embodiment shown in FIG. 10;

FIG. 14 is a top plan view of the embodiment shown in FIG. 10;

FIG. 15 is a bottom plan view of the embodiment shown in FIG. 10;

FIG. 16 is a cross-sectional view of the embodiment shown in FIG. 10 taken along line 16-16 of FIG. 14;

FIG. 17 is a top plan view of the embodiment shown in FIG. 10 showing the hinged tops in their open horizontal position;

FIG. 18 is a front elevational view of the right portion of the embodiment shown in FIG. 10; and

FIG. 19 is a rear elevational view of the left portion of the embodiment shown in FIG. 10.

This is a continuation-in-part of design application Ser. No. 315,512, filed Dec. 15, 1972, and now abandoned.

I claim:

The ornamental design for an automobile console, substantially as shown and described.
